UNITED STATES PATENT OFFICE.

JAMES N. LEE, OF BROOKLYN, NEW YORK, ASSIGNOR OF ONE-HALF TO GRAMBERRY SUTTON, OF BROOKLYN, NEW YORK.

SCREW.

1,091,674.

Specification of Letters Patent. Patented Mar. 31, 1914.

Application filed September 2, 1913. Serial No. 787,773.

To all whom it may concern:

Be it known that I, JAMES N. LEE, a citizen of the United States, residing at Brooklyn, in the county of Kings and State of New York, have invented certain new and useful Improvements in Screws, of which the following is a specification, reference being had to the accompanying drawings.

This invention relates to new and useful improvements in screws or bolts and the like and the primary object of the invention resides in providing a device of this character which is provided with means for absolutely preventing the removal thereof, after having once been positioned in the wood.

A further object of the invention resides in providing a screw or bolt with a pivoted blade at its lower end for lateral disposition after the screw or bolt has been properly inserted in the wood, whereby to prevent the removal of said screw or bolt and a still further object resides in providing means for operating the blade.

Still another object of the invention resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawing forming a part of this application, Figure 1 is an elevation of the device showing the blade disposed to its effective position. Fig. 2 is a vertical section therethrough showing the blade in its inoperative position. Fig. 3 is a horizontal section through the same as seen on line 3-3, Fig. 2. Fig. 4 is an elevation of the knife blade removed. Fig. 5 is a similar view of the punch used in the operation of the device. Fig. 6 is a plan view of the bolt; and Fig. 7 is a bottom plan view of the punch used in the device.

In describing my invention, I shall refer to the drawing in which similar reference characters designate corresponding parts throughout the several views and in which-

1 indicates a metal screw or bolt, preferably the former, the head 2 of which is provided with the transverse slot 3 which is usually provided in screws. This screw or

bolt 1 is provided with a central longitudinal bore 4, which communicates at its upper end with the slot 3 in the head and which communicates at its lower end with a slot formed by bifurcating the lower end of the bolt or screw 1, as shown at 5.

Pivots mounted on a pin 6 extending transversely through the bifurcated and tapered lower end of the bolt or screw 1, is a substantially diamond-shaped blade 7, 65 the opposite edges A and B of which are sharpened to provide knife edges. This blade 7 is of such size as to be entirely enclosed within the slot in the lowermost end of the screw or bolt 1, when disposed in its normal position and one side edge thereof between the knife edges A and B, is offset to provide a shoulder 8 and a continuing beveled or inclined edge 9. In the normal position of this blade 7, within the lower end 70 of the screw or bolt 1, this beveled or inclined edge 9 leading from the shoulder 8 is disposed upwardly and directed toward the lower end of the bore 4, the purpose of which will be hereinafter and more particularly 80 described. In order to operate this blade 7, I have provided a rod 10 which is adapted to be disposed through the longitudinal bore 4 of the screw or bolt 1, the lower end thereof being adapted to contact with the inclined or beveled edge 9 of the blade to force the same somewhat laterally, whereby the cutting edges A and B may be disposed in opposite directions beyond the lower end of 85 said bolt or screw. In order to force this 90 rod 10 downwardly against the blade, I have provided a punch which consists of a handle member or the like 11, the lower end of which is enlarged and provided with a stud or prong 12. This prong or stud 12 is 95 adapted to be passed through the slot 3 of the head of the screw or bolt to engage with the upper end of said rod 10. When the hammer is applied to the upper end of the 100 punch, it is obvious that the rod 10 may be forced downwardly to force the cutting edges A and B of the blade outwardly into engagement with the wood of an object in 105 which this screw or bolt is applied.

In applying the device to use, the screw or bolt 1, with the blade therein is first applied in the usual manner to an object, and the rod 10 is then applied in the bore 4 thereof. The punch is then properly introduced into the head of the screw or bolt so that the 110

prong or stud 12 engages the upper end of said rod, whereupon a hammer is applied to the punch. As the rod 10 is forced inwardly, the lower end of the same will contact with the inclined or beveled edge 9 of the blade 7. It is obvious that with such an engagement of the blade, the latter will be swung on its pivot so that the cutting edges A and B thereof will be disposed outwardly 10 in opposite directions to project beyond the slot in the lower end of the screw or bolt 1. This blade will cut its way through the wood and thus securely hold the bolt or screw in the desired position. The punch 15 may then be removed and it will be seen that the bolt or screw cannot be removed without splitting the wood in which the same is disposed.

From the foregoing it will be seen that I 20 have provided a device which is simple and durable in construction, inexpensive to manufacture and one which will be very efficient and useful in operation and while I have particularly described the elements 25 best adapted to perform the functions set forth, it is obvious that various changes in form, proportion and in the minor details of construction may be resorted to without departing from the spirit or sacrificing any 30 of the principles of the invention as defined by the appended claims.

Having thus described this invention, what is claimed is:—

1. A screw or bolt of the class described 35 comprising an elongated body having a central longitudinal bore, the lower end of said body being tapered and bifurcated, the slot

forming the bifurcation communicating with the lower end of said bore, a head formed on the body having a slot therein 40 communicating with the upper end of said bore, a blade pivoted in the bifurcated lower end of said body, the one edge of said blade being offset to provide a shoulder and an inclined continuing edge, and means 45 adapted for introduction through the bore of the body to engage the inclined edge and shoulder on the blade and swing the latter on its pivot.

2. In a device of the class described, an 50 elongated threaded body having a central longitudinal bore, the lower end of said body being tapered and bifurcated, the slot forming the bifurcation being designed for communication with the lower end of said 55 bore, a head member formed on the body having a slot therein communicating with the upper end of said bore, a substantially diamond-shaped blade pivoted on a transverse axis in the bifurcated lower end of 60 said body, one edge of said blade being offset to provide a shoulder and an inclined continuing edge, said shoulder and edge being normally directed upwardly toward the bore of the body, and means adapted for 65 introduction through the bore of said body to engage the inclined edge and shoulder on the blade and swing the same on its pivot.

In testimony whereof I hereunto affix my 70 signature in the presence of two witnesses.

JAMES N. LEE.
